No. 738,474.

PATENTED SEPT. 8, 1903.

B. F. OREWILER.
GARMENT SUPPORTER.
APPLICATION FILED MAR. 7, 1902

NO MODEL.

UNITED STATES PATENT OFFICE.

BENJAMIN FRANKLIN OREWILER, OF CHICAGO, ILLINOIS, ASSIGNOR OF
ONE-HALF TO GEORGE H. REINBERGER, OF CLEVELAND, OHIO.

GARMENT-SUPPORTER.

SPECIFICATION forming part of Letters Patent No. 738,474, dated September 8, 1908.

Application filed March 7, 1902. Serial No. 97,072. (No model.)

To all whom it may concern:

Be it known that I, BENJAMIN FRANKLIN OREWILER, a citizen of the United States, residing at Chicago, in the county of Cook and State of Illinois, have invented a new and useful Garment-Supporter, of which the following is a specification.

This invention relates to garment-supporters, and is directed more particularly to the improvement of the clasp by means of which the supporter is attached to a stocking or other garment.

The clasp most commonly employed on hose-supporters comprises a loop member and a button member retained at one end of a suspending tape. The loop member is of elongated form, and one end thereof is narrowed or constricted to receive the shank of the button, over the head of which the garment is placed. The protection of the fabric from injury has been insured by various expedients, the most successful of which comprehends the use of a rubber or other elastic button, the yielding nature of which prevents the fabric from being cut by the edges of the loop member contacting therewith. This rubber or elastic button is expensive, however, and after continued use loses its elasticity and becomes hard and worthless so far as the protection of the fabric is concerned.

My invention has for its object to produce a clasp eliminating the elastic button and securing the necessary elasticity of the engaging parts by equipping the loop member with a spring lock or grip corresponding generally to the form of the loop, but disposed within the latter to constitute the button-engaging portion of the loop member.

Another object of the invention is to combine the loop proper with the spring-lock or button-engaging member that the relatively movable portions of the latter will have interfitting engagement with the loop and will be retained in proper position and guided thereby in such movements as are necessary to the engagement and disengagement of the button.

Other objects of the invention and advantages of the clasp will appear more fully in the course of the succeeding description of those embodiments of the invention which I

have selected for illustration in the accompanying drawings.

In said drawings, Figure 1 is a front elevation of so much of a garment-supporter as is necessary to illustrate the construction of the clasp and the manner in which it is attached to a garment. Fig. 2 is a view similar to Fig. 1, showing the cap or keeper at the lower end of the loop broken away to illustrate hidden parts. Fig. 3 is an elevation of the reverse side of the subject-matter of Fig. 2 with the button member detached. Fig. 4 is a longitudinal sectional view of the subject-matter of Fig. 1. Fig. 5 is a front elevation of another form of clasp or loop member therefor. Fig. 6 is a longitudinal section of the subject-matter of Fig. 5. Fig. 7 is a front elevation of still another form of loop member. Fig. 8 is a longitudinal section thereof. Fig. 9 is a detail perspective view of the button-plate with the button detached and showing the toothed end bar offset from the plane of the plate. Fig. 10 is a detail sectional view of the button member, showing the manner in which the tape is threaded through the button-plate; and Fig. 11 is a view similar to Fig. 10, but showing the toothed bar sprung back into the plane of the plate to cause the retention of the tape by the teeth.

Like numerals of reference are employed to designate corresponding parts throughout the several views.

The supporter comprises, as usual, a suspending-tape 1, at the lower end of which is retained a garment-clasp comprising a loop member 2 and a button member 3. In that form of my invention illustrated in Figs. 1, 2, 3, and 4, which I shall first describe, the loop proper is stamped or otherwise formed from sheet metal and is provided at its upper or wide end with a slot 3^a to facilitate the attachment of the tape. The lower or narrow end of the loop is provided with a second slot 4, through which extend the ends 5 and 6 of what may be termed the "rear member" or "spring lock" 7 of the loop. The member 7 has the general form of a loop divided at its lower end and is preferably formed from a single piece of spring-wire bent to approximate the form of the loop proper and secured at its upper or closed end to the upper end of the

loop by any suitable means. The means for connecting the members 2 and 7—that is to say, the loop proper and the spring-lock—will in practice be a portion of the tape 1, which 5 as shown in the drawings (particularly in Fig. 4) is passed through the slot 3^a, around the upper transverse end of the member 7, and sewed or otherwise secured to connect the members of the loop and to furnish a loose 10 end 8 for the attachment of the button member. The rear spring-wire member 7 while approximating the form of the loop 2 has its opposite side portions extended within the inner edges of the loop and bent, as indicated 15 at 9, to form a constricted throat 10, (see Fig. 3,) below which the sides of the member 7 diverge, so that after the shank of the button has been forced past the throat 10 the sides 20 of the spring-lock may assume their normal positions and bear upon the fabric with just sufficient pressure to secure a firm grip without endangering the integrity of the fabric. The rigid loop 2 and the spring member 7 lie close against each other, as shown in Fig. 4. 25 Therefore in order to provide for their interfitting engagement at the lower end of the clasp, to insure the proper guiding of the yielding sides of the member 7, and to limit the expansion thereof it is necessary that a 30 portion of one of said members be bent out of the plane of the body thereof. In the form illustrated in the first four figures such interfitting engagement is secured by bending the opposite sides of the spring member and passing 35 them through the slot 4 in the member 2, at the front side of which the extremities of the spring-lock are bent into parallel relation with the member 2 and terminate just short of the lower extremity thereof. If desired, 40 these spring ends 5 and 6 may be bent back to form terminal eyes, as best shown in Fig. 2, or, as shown in Fig. 5, these eyes may be omitted. To provide a neat finish for the clasp and also to obscure and protect the 45 lower ends of the spring member 7, the loop 2 may be provided at its lower end with a cap or keeper 11, preferably formed by bending over a pair of lug 12 and 13, which in stamping the 50 member 1 are permitted to extend laterally in opposite directions from the lower end thereof. In practice the fabric—as, for instance, the upper edge of a stocking—is placed over the button, and the head of the latter is passed through the upper or wide end of the loop 55 from the rear. The button is then drawn down, and the shank thereof is presented to the constricted throat of the spring-lock, the sides of which will be sprung apart to permit the button to be drawn down to the lower 60 narrow or button-receiving end of the loop. As the sides of the spring-lock are bent out below the throat 10 said sides will spring back substantially to their normal positions after the button has reached the lower end of the 65 loop, the constricted throat will be re-formed above the shank of the button, and the displacement or disengagement of said button

will therefore be prevented, except by such positive movement thereof as will serve to overcome the resistance of the lock. At the 70 same time the engagement of the fabric will not be more severe than is necessary to secure a firm grip, and the spring-wire being rounded will prevent the fabric-engaging portions thereof from injuring the garment. 75

In Figs. 5 and 6 I have illustrated another form of the invention, which differs from the form first described in the omission of the cap or keeper 11 and in the deflection of the loop instead of the spring-lock to accommodate the 80 interfitting engagement of these parts. The loop 2 is stamped from sheet metal, as in the first form, and is slotted at its lower end in the same manner. Instead, however, of the lower end of the spring member being offset 85 from the body portion thereof for reception within the slot the lower end of the member 2 is offset from the plane of the member, as indicated at 14 in Fig. 6, and the terminal eyes of the spring member are omitted. This 90 latter form (illustrated in Figs. 5 and 6) embodies all of the leading characteristics of the first form of the invention, but is devised with special reference to the production of an inexpensive clasp for use in hose-supporters 95 of an inferior grade.

Still another form of the invention is illustrated in Figs. 7 and 8, wherein the loop 2^a is formed from wire instead of being stamped from sheet metal, and instead of the lower 100 ends of the spring-lock being passed through a slot in the loop the end of said loop is received within a pair of terminal eyes 5^a and 6^a, formed by bending the extremities of the 105 spring-wire from the plane of the body portion thereof, as shown in Fig. 8. The sides of the loop 2^a limit the expansion of the spring-lock in this last-described form just as the 110 ends of the slot 4 limit such expansion in the preceding forms of the invention; but it will 115 be observed that in all forms an interfitting engagement is secured between the loop and the lower ends of the spring-lock member by bending the end of one of said members out of the plane of its body portion to facilitate such engagement.

It will be noted that the invention comprehends a clasp-loop member comprising a rigid or substantially inelastic loop associated with a divided spring-loop substantially co-extensive therewith longitudinally and constituting a yielding constriction of the rigid loop for the purpose of providing a spring-lock which while gripping the fabric firmly will be sufficiently yielding and devoid of sharp surfaces to reduce to a minimum the liability of cutting the fabric, notwithstanding the elimination of the yielding button surface.

A button-supporting plate of peculiar construction (illustrated in Figs. 9, 10, and 11 of the drawings) constitutes another of the novel features of the invention. It is desirable to provide means whereby the button-plate may

be attached to the end of the tape or web without sewing. To attain this end, I form the button-plate 15 from pliable sheet metal and with transverse arcuate slots 16 and 17 at its opposite ends. These slots separate the comparatively thin light end bars 18 and 19 from the body of the plate, and the bar 19 is provided with a series of teeth 20, which when the bar lies in the plane of the body of the plate extend from said bar to the edge 21 of the plate proper. When the plate is manufactured, however, the end bar 19 and the teeth are struck down, so as to lie offset in a plane parallel with the plate proper, but removed therefrom sufficiently to permit the end of the tape 1 to be slipped through the slot 18, thence under the body of the plate and under the bar 19, thence around the bar and under the body of the plate. As the teeth lie perfectly flat and in a plane parallel with the plate the extremity 22 of the tape 1 is passed through the slot 17 without difficulty. After the tape has been inserted in the manner stated the bar 19 is forced back into the plane of the plate, and the teeth are thereby forced simultaneously through the tape to hold the latter securely against withdrawal. It will be noted that the metal at the ends of the slot 17, connecting the bar 19 with the body of the plate, is in the form of narrow strips, which while permitting the teeth-carrying bar to be readily pressed back into the plane of the plate from its offset position are sufficiently strong to resist any ordinary strain which might tend to release the tape from the button-plate.

From the foregoing it will be observed that I have produced a simple and effective clasp for garment-supporters; but while the described embodiments of the invention appear at this time to be preferable for certain lines of trade I desire to reserve the right to effect such changes, modifications, and variations of the illustrated structure as may be suggested by experience and experiment and embraced within the scope of the protection prayed.

What I claim is-

1. A loop member for garment-clasps, comprising a rigid loop, and a spring-loop associated therewith, said spring-loop having a wide upper end, a divided lower end and an intermediate constricted throat, the extremities of the spring-loop having sliding engagement with a transversely-disposed portion of the rigid loop.

2. A loop member for garment-clasps, comprising a rigid loop, and a spring-loop retained at the upper end of the rigid loop and having a constricted throat and a divided lower end, the extremities of the spring-loop having lateral sliding engagement with the transverse end portion or bar of the rigid loop.

3. A loop member for garment-clasps, comprising a rigid loop, and a divided spring-loop associated therewith and having a constricted throat intermediate of its ends, the

terminals of the divided loop having interfitting engagement with lower end of the rigid loop.

4. A loop member for garment-clasps, comprising a rigid loop, and a divided spring-loop associated therewith and having a constricted throat intermediate of its ends, said spring-loop being retained at the upper end of the rigid loop and its terminals being disposed in interfitting relation with the lower end of said rigid loop.

5. A loop member for garment-clasps, comprising a rigid loop, and a divided spring-loop having its opposite ends secured to the opposite ends of the rigid loop and provided with a constricted throat intermediate of its ends.

6. A loop member for garment-clasps, comprising a rigid loop provided with a slot, and a divided spring-loop formed with a constricted throat and associated with the rigid loop, said spring-loop having its terminals received within said slot.

7. A loop member for garment-clasps, comprising a rigid loop provided with a transverse slot at its lower end, and a divided spring-loop secured at its upper end to the upper end of the rigid loop and provided intermediate of its ends with a constricted throat, the terminals of the spring-loop being received within the slot of the rigid loop.

8. A loop member for garment-clasps, comprising a rigid loop having a transverse slot at its lower end, a spring-loop longitudinally coextensive with the rigid loop and having a constricted throat, and also having a divided lower end extended through the slot, means for connecting the loops at their upper ends, and a keeper or guard carried by the rigid loop and serving to cover and protect the terminals of the spring-loop.

9. In a garment-supporter, the combination with a suspending-tape, and a button member secured thereto, of a loop member comprising a rigid loop and a spring-loop secured in proper relative positions by the tape, said loop member being provided intermediate of its ends with a constricted throat, and having a divided lower end in interfitting engagement with the lower end of the rigid loop.

10. In a garment-supporter, the combination with a suspending-tape, and a button member secured thereto, of a loop member comprising a rigid loop having a transverse slot at its lower end and a guard or keeper extending over the slot, and a spring-loop secured to the upper end of the rigid loop by the suspending-tape, said spring-loop having a constricted throat intermediate of its ends and a divided lower end passed through the slot of the rigid loop and protected by the guard or keeper.

11. A loop member for garment-clasps, comprising a rigid loop, and a spring-loop associated therewith, said spring-loop being divided at one end, provided with a constricted throat intermediate of its ends and widened

at a point between the throat and the divided end.

12. A loop member for garment-clasps, comprising a rigid loop, and a spring-loop associated therewith, said spring-loop being divided at its lower end, provided with a constricted throat intermediate of its ends and widened at a point between the throat and the divided end, the extremities of the spring-loop at opposite sides of the division being normally in closely-adjacent relation, where-

by the shank of a button when located between the divided end of the loop and the constricted throat will be gripped by the spring-loop.

In testimony that I claim the foregoing as my own I have hereto affixed my signature in the presence of two witnesses.

BENJAMIN FRANKLIN OREWILER.
